UNITED STATES PATENT OFFICE.

IRVIN F. McDONALD, OF BALTIMORE, MARYLAND.

BUTTON-FASTENER.

1,267,243.

Specification of Letters Patent. Patented May 21, 1918.

Application filed March 2, 1917. Serial No. 152,097.

To all whom it may concern:

Be it known that I, IRVIN F. McDONALD, a citizen of the United States, residing at Baltimore, in the State of Maryland, have invented certain useful Improvements in Button-Fasteners, of which the following is a specification, reference being had therein to the accompanying drawing.

The present invention has reference generally to improvements in that class of inventions known as buckles, buttons and clasps and more particularly relates to an improved button fastener.

As the primary aim and object, this invention contemplates the provision of novel means formed on the button attaching member for coöperation with the eye on the button in such a manner as to constitute an abutment to enable the spring arms of the attaching member to clasp the eye whereby the attaching member will be projected from the rear face of the button and owing to the inherent resiliency of the arms thereof will be maintained in such position to consequently facilitate the application of the attaching member in a button hole on a garment.

It is an additional and equally important object of the present invention to so construct the button engaging means that it will overlie and extend beyond the terminal of the other arm of the attaching member, thus preventing accidental disengagement of the button from the attaching member.

The invention as a further improvement consists in the constructing of the eye engaging member on one end of the attaching member so that it will serve as an abutment for coöperating with the eye of a button when the button and the attaching member is being withdrawn.

More particularly, the present invention embraces the provision of an attaching member formed from a single piece of resilient metal and comprising a pair of resilient arms between which is slidably engaged the eye of the button one of the arms being incidentally provided intermediate its ends with a button engaging portion consequently enabling the portion of the arms to the side of the button receiving portion to coöperate with an article of apparel for retaining the button against accidental displacement.

Among the other aims and objects of the present invention may be recited the provision of a device of the character mentioned

with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention, should be considered in connection with the accompanying drawings forming a part hereof, and wherein is disclosed for the purpose of illustration a convenient and satisfactory embodiment of the invention. It is to be noted in this connection that minor changes in the construction and arrangement of the parts may be made without departing from the spirit or the principle of operation of the various parts.

The preferred embodiment of the present invention is clearly illustrated in the accompanying drawings, in which:—

Figure 1 is a side elevation of the invention, a portion of the garment to which the button is applied being shown in dotted lines.

Fig. 2 is a side elevation showing the position assumed by the parts when the button is being withdrawn from engagement with the portion of an article of apparel, shown in section.

Fig. 3 is a front elevation of the invention the parts being shown in the position assumed when the device is being applied.

Fig. 4 is a side elevation of the same.

Fig. 5 is an enlarged transverse section taken through a piece of wire from which the attaching member is formed.

Similar characters of reference are employed in all of the above described views, to indicate corresponding parts.

Referring now, more particularly, to the accompanying drawings, there is provided a button 1 in the rear face of which projects an eye 2 slidably engaged with the improved attaching member indicated in its entirety by the numeral 3.

In the present instance the improved attaching member is formed desirably from a single piece of resilient metal such as wire, desirably but not necessarily of a semi-circular form in cross section, the piece of metal being bent upon itself intermediate its ends 105 110 to provide resilient arms 4 and 5. It will be observed that the strip at its point of

distortion is flattened so that the flattened surfaces of the wire are arranged in close relation with each other consequently assuming a substantially circular form for 5 facilitating the application of the attaching member in a manner that will be hereinafter apparent, while in addition the flat surfaces of the metal strip are normally arranged in yielding engagement with each 10 other throughout their length. The arm 5 is offset intermediate its ends to provide a U-shaped button receiving portion 6, the offset portion lying in a plane which is common to both arms. A hook 7 is formed on 15 the terminal of the arm 5, the bend 8 thereof being offset in the plane of the offset portion 6 while the bill 9 thereof is straight and is extended in a plane at approximately right angles from the longitudinal axis of 20 the arm 5 to project over and beyond the terminal of the other arm 4 being arranged in close relation with the terminal of the arm 4. The eye 2 of the button is insertible between the free end of the bill and the 25 terminal of the arm 4 when the arms are extended and is slidably arranged between the flat faces of the arms so as to be engaged in the bend of the hook 8 or in the U-shaped portion 6, being prevented from displacement 30 from the attaching member owing to the elongated bill 9 of the hook.

In use, in attaching the button the attaching member 3 is raised to assume a position perpendicular to the rear face of the button 35 whereupon the eye is moved between the arms 4 and 5 until the bill strikes the inner portion of the eye as indicated in Fig. 4, the parts being maintained in this position owing to the resiliency of the arms and obviously permits of a ready application of the attaching member through a button hole 10 in an article of apparel 11. Subsequent to passing the attaching member through the button hole 10 the eye of the button is 45 moved between the arms so as to be received in the offset portion 6 and retained against displacement by the arm 4, the attaching member of course being arranged on the inside of the garment while the arms serve to 50 retain the button against accidental displacement. In withdrawing the button the eye is again slid between the arms 4 and 5 and arranged in the hook 7 and by exerting

a pull on the button it can be readily removed from position. During this action 55 of removing the button it will be observed that the bill of the hook serves as an abutment for the outer portion of the eye. Likewise it will be appreciated that this same bill serves as an abutment when the button 60 is being applied. It will also be appreciated that because of the arrangement of the flat surfaces of the piece of wire opposite to each other at the outer ends of the arms that an effective engagement will be obtained by 65 the arms with the eye.

As many changes could be made in the above construction and many apparently widely different embodiments of this invention could be made without departing from 70 the scope thereof, it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope 75 of the invention, which, as a matter of language might be said to fall therebetween.

Having thus fully described this invention, what is claimed and desired to be secured by Letters-Patent, is:—

In a button fastener, the combination with 85 a button, an eye projecting from the rear face thereof, of an attaching member formed from a single piece of resilient wire bent upon itself to provide a pair of resilient arms normally arranged in yielding 90 relation with respect to each other throughout their length and between which arms is slidably arranged and supported the eye of the button, a U-shaped button receiving portion formed in one of the arms, and a hook 95 formed on the terminal of the same arm and having the bill thereof projecting at right angles to the arm and projected over and extended beyond the terminal of the other arm and arranged in close relation therewith for 100 preventing accidental disengagement of the eye and serving as an abutment for coöperating with the eye in applying and removing the button.

In testimony whereof I affix my signature. 105
IRVIN F. McDONALD.
